United States Patent Office

ANTOINE ST. LOUIS, OF KEESEVILLE, NEW YORK.

Letters Patent No. 66,906, dated July 16, 1867.

IMPROVEMENT IN MACHINES FOR MAKING SPIKES AND NAILS.

The Schedule referred to in these Letters Patent and making part of the same.

TO ALL WHOM IT MAY CONCERN:

Be it known that I, ANTOINE ST. LOUIS, of Keeseville, in the county of Clinton, and State of New York, have invented certain new and useful improvements in "Nail and Spike Machines;" and do hereby declare that the following is a full, clear, and exact description thereof, reference being had to the accompanying drawings, and to the letters of reference marked thereon.

In the annexed drawings, making part of this specification, A A' represent the frame of the machine, which is made in a very firm and substantial manner, A representing the sides and A' the ends of said frame. Erected upon the sides A are two uprights, B B, which support a cam-shaft, B'. J and I represent shafts which run from end to end of the frame, and which are supported in proper bearings in said ends. These shafts support the anvils. The shaft I supports the hammers H H', and shaft J supports the anvils K and L. These anvils have openings in their lower ends through which the shafts pass. Q represents a shaft situated at one side of the frame and supported upon suitable uprights erected upon the end pieces at their ends. Upon this shaft Q is secured a gear-wheel, R, three cam-wheels, P, P', and S, and also a wheel, y, which has lugs upon its periphery at suitable distances apart for the purpose of operating a lever which carries a knife for cutting off the nail. The two cam-wheels P P' operate the levers O and M, which said levers operate respectively the anvils K and L, giving them a slightly oscillating movement to and from the hammers H H'. The levers O and M have their ends which lie upon the cam-wheels P and P' drawn down upon said wheels by means of suitable springs. The lever X also has its outer end confined to the periphery of its wheel y by a spring so that it may be properly operated upon by the lugs on said wheel. The hammers H H' being confined securely to their shaft I have motion imparted to them by means of a lever, Z', whose outer end connects to the lower end of a bar, Z. The upper end of bar Z is provided with an opening which surrounds an eccentric-wheel upon shaft B'. When the shaft B' is rotated, the bar Z, through its lever Z', gives a slightly oscillating movement to the upper ends of the hammers H H', to and from the anvils K and L. D represents a lever, which has one end pivoted to a support which is erected upon one end of the frame, and its other end pivoted to the upper end of the hammer F. This lever has secured upon its under side a hammer, E. The hammer F is provided with an opening, in which fits an eccentric-wheel upon shaft B'. This eccentric-wheel causes the hammer to rise and fall, giving an oscillating motion to the lower end of the anvil, which said lower end is provided with a roller, G. On one end of the shaft B' is a wheel, T, which has a-thread formed upon its periphery, which said thread works between the teeth of the gear-wheel R. Motion is imparted to the hammers H H' by the shaft B' when power is applied to revolve said shaft. V V represent two ways secured upon one side of the anvil L, which are provided with a T-shaped groove, in which runs a similar-shaped slide, W'. Secured to the slide W' is a griper, W. The inner end of said griper is pivoted between two ears on the slide, and the outer end runs over one of the ways. The bar of iron of which the nail is to be formed is placed upon the slide W', beneath that end of the griper which is confined between the ears upon said slide. That way over which the outer end of the griper rests is slightly bevelled, so as to allow said outer end to fall slightly while the inner end is raised to allow the bar of iron to be passed under it. When the slide moves inward, the griper, rising upon the bevelled way, clamps the bar tightly with its inner end upon the slide. A lever, U, pivoted near one end to one of the side pieces of the frame, is operated upon at its outer end by means of the cam-wheel S. The other end of said lever is slotted, and through this slot is connected by means of a pin to the slide W'. A spring, d, draws this lever U against the cam-wheel S. The lever U operating the slide W', serves to feed the bar of iron to the anvils.

In using this invention the bar of iron is placed upon the slide W', beneath the inner end of the griper, and is caught by the said griper W and is fed up to the anvil by means of the spring d. The cams upon wheel S operate the lever U, causing it to draw the slide with its griper back after the said slide has been moved forward so as to feed up the bar to the anvils by means of spring d. When the bar has been placed between the anvils and the hammers, they work upon it, drawing and shaping it properly. The nail, after passing the hammers F and H' and anvil L, passes to the anvil K and hammers H and E, where it is pointed, planished, and then cut off by the knife or cutter a on the lever X. As soon as the nail is cut off, the anvil K is moved back by the lever O so as to allow the nail to drop out of the way, it falling down between the anvil K and hammer H.

As fast as one nail is cut off another is brought up by the griper and undergoes the same operation. Ledges are formed upon the anvils the size the nail is intended to be, and on which it lies, as seen at *e*, figs. 3 and 5.

Having thus fully described my invention, what I claim as new, and desire to secure by Letters Patent, is—

1. The arrangement of the moving anvils K and L, the side hammers H H', with the hammers E and F, the latter being provided with a roller-face, as and for the purpose set forth.

2. The combination of the slide W' and griper W with the ways V V, lever U, and cam-wheel S, substantially as and for the purpose set forth.

3. The combination of the knife or cutter *a* with the anvil K and hammers E and H, substantially as herein represented.

In testimony that I claim the foregoing I have hereunto set my hand this 4th day of February, 1867.

ANTOINE ST. LOUIS.
